UNITED STATES PATENT OFFICE.

WILLIAM F. KELLETT, OF CHICAGO, ILLINOIS.

DESIGN FOR A PLASTER CENTER-PIECE.

SPECIFICATION forming part of Design No. 14,324, dated September 25, 1883.

Application filed December 1, 1882. Term of patent 14 years.

To all whom it may concern:

Be it known that I, WILLIAM F. KELLETT, a citizen of the United States, residing at Chicago, in the county of Cook and State of Illinois, have invented and produced a new and original Design for Plaster Center-Pieces for Rooms, of which the following is a true and correct specification, reference being had to the accompanying engraving, which shows the 10 pointed frames in my design with groups of flowers in relief and masses of conventional geranium-leaves bounded by crocketed perpendicular arches, all of which fully show my design.

15 My design consists of a pointed frame of scallop-work and center with radiating arms, as shown in the figure. Each frame contains four panels composed of groups of flowers of different varieties, as shown in said figure. To

this pointed frame I add or connect wings composed of masses of conventional geranium-leaves bounded by crocketed perpendicular arches, as shown in the figure. Whenever I deem it desirable, I omit from my design the crocketed perpendicular arches, as occasion 25 may require.

I claim—

A pointed frame of scallop-work and center with radiating arms, such frame containing 30 panels of groups of flowers with wings of conventional geranium-leaves bounded by crocketed perpendicular arches, all substantially as shown and described.

WILLIAM F. KELLETT.
